(57) **CLAIM**

The ornamental design for a skin care apparatus, as shown
and described.

DESCRIPTION

FIG. 1 is a perspective view of a skin care apparatus showing
our new design;

FIG. 2 is a rear perspective view of the design;

FIG. 3 is a front view of the design;

FIG. 4 is a rear view of the design;

FIG. 5 is a left side view of the design;

FIG. 6 is a right side view of the design;

FIG. 7 is a top view of the design;

FIG. 8 is a bottom view of the design; and,

FIG. 9 is a perspective view of the skin care apparatus
showing our new design in a state in which the eyeglass legs
are folded.
